CLAIM

The ornamental design for a protective helmet as shown and described.

DESCRIPTION

1. Protective helmet

1.1 is an isometric view of the protective helmet wherein an eye shield and a full face visor are in retracted positions, respectively.

1.2 is a front view of the protective helmet wherein the eye shield and the full face visor are in the retracted positions, respectively.

1.3 is a rear view of the protective helmet.

1.4 is a top view of the protective helmet wherein the eye shield and the full face visor are in the retracted positions, respectively.

1.5 is a right-side view of the protective helmet wherein the eye shield and the full face visor are in the retracted positions, respectively.

1.6 is a left-side view of the protective helmet wherein the eye shield and the full face visor are in the retracted positions, respectively.

1.7 is an isometric view of the protective helmet wherein the eye shield is in an extended position and the full face visor is in the retracted position.

1.8 is a front view of the protective helmet wherein the eye shield is in the extended position and the full face visor is in the retracted position.

1.9 is a left-side view of the protective helmet wherein the eye shield is in the extended position and the full face visor is in the retracted position.

1.10 is an isometric view of the protective helmet wherein the eye shield and the full face visor are in extended positions, respectively.

1.11 is a front view of the protective helmet wherein the eye shield and the full face visor are in extended positions, respectively.

1.12 is a bottom view of the protective helmet wherein the eye shield and the full face visor are in extended positions, respectively.

The reflections and shadows appearing in the reproductions are not part of the design for which protection is claimed. The interior features of the helmet comprising the headliner, top-of-skull padding, side padding, rear-of-skull padding, cheek padding, forehead padding, and the chin straps and buckles, and the interior seams and interior joints of the shell of the protective helmet are not part of the design for which protection is claimed. However, both the eye shield and the full face visor are part of the design for which protection is claimed.
